UNITED STATES PATENT OFFICE.

WILLIAM STEWART, OF WEST KOGARAH, NEW SOUTH WALES, AUSTRALIA.

ELECTRIC PLUG AND SOCKET CONNECTION.

1,303,609.

Specification of Letters Patent. Patented May 13, 1919.

Application filed August 21, 1917. Serial No. 187,460.

To all whom it may concern:

Be it known that I, WILLIAM STEWART, a subject of the King of Great Britain, residing at "Glenrock," Warriarda street, West 5 Kogarah, in the State of New South Wales and Commonwealth of Australia, electrician, have invented a new and useful Improvement in and relating to Electric Plug and 10 Socket Connections, of which the following is a specification.

This invention relates to the plug and socket connections or unions of electrical circuits as for electric bulbs or lamps, domestic irons, toasters and other devices and 15 has been specially devised in order to provide cheap, handy and effective means whereby the connecting plug as of a bulb or lamp when inserted in the socket cannot be withdrawn again until the lamp is broken or the 20 lock on said plug destroyed and thus prevent the connection being broken, disjointed, or parted and the lamp or other device being removed or stolen and thus further prevent the socket being used for other or illegitimate 25 purposes as by occupiers of rooms or apartments connecting radiators or other current consuming devices to electric light circuits.

According to this invention a collar or 30 locking band adapted to revolvably fit on the ordinary connecting sockets has intruding slots from one end and carries on or in its outer wall a spring with inwardly bent end or ends or pin or pins adapted to intrude 35 beyond the inner periphery of said wall when no resistance is offered as when said spring armed locking band positioned over the socket with its intruding slots coinciding with the bayonet slots of said socket is 40 slightly revolved from said coincident position to the holding position of said socket after the retaining pintles of the plug are inserted through said coincident slots. An outer loose thimble or shield is positioned 45 over the locking band before mentioned when said band is over the socket so as to inclose the spring. This shield abuts against the holding nut of the socket or against a washer held thereby and reaches to the shoulder of the plug or of its affixed lamp or fitting or to a washer in turn abutting said shoulder, or the shield may have an integral flange or be contracted at either end to abut 50 the socket or plug end fittings or contours. 55 In carrying this invention into practical

effect the various parts may have many modifications within the scope and for the purposes above set out but in order that the carrying out of said invention may be easily put into practice the now best known manner 60 of doing so will be described with reference to the drawings accompanying and forming part of this complete specification.

Figure 1 is a perspective view of a plug and socket union and lock with its parts dis- 65 assembled. Fig. 2 is a similar view showing some parts assembled ready to complete the union and lock. Fig. 3 is another similar view showing all the parts assembled and the union and lock completed. Fig. 4 70 is an elevation partly in section of the completed union and lock as in Fig. 3. Fig. 5 is a sectional plan on plane 5—5, Fig. 2. Fig. 6 is a sectional plan on line 6—6, Fig. 4. Fig. 7 is an enlarged sectional perspective 75 view of a locking band on a socket wall. Figs. 8 and 9 are sectional elevations illustrating modified constructions of lock shields.

The collar or locking band 12 with slots 80 13 carries spring 14 with inturned ends 15 passing through orifices 16. The shield 21 adapted to take over the locking band is of sufficient length to comfortably fit between an abutment on the socket and one on the 85 base or plug of a lamp or other like fitting.

To insert the plug end 17 of a lamp 18 or other appliance in the socket end 19 of a union or connection and lock it therein the locking band 12 with its spring 14 is placed 90 over the socket 19 its slots 13 being positioned coincident with the slots 20 of said socket and the inturned ends of the spring 15 comfortably loosely fitting the orifices 16. A thimble or shield 21 is placed over the 95 plug 17 both as shown in Fig. 2 and the parts are then ready to be joined together to consummate the union and the lock as shown in Fig. 3. In joining these parts the pintles 22 on the plug 17 are intruded 100 in the coincident slots 13 and 20 as the lamp or other device is pushed inwardly as far as it will go and then partially revolved to move the pintles 22 into the angular extension of the slots 20 and which movement 105 carries the locking band around on the socket 19 until the spring ends 15 pass into said slots 20 or the extensions thereof (or into the supplementary orifices or pin holes provided therefor). The plug 17 is thus 110

22 prevented from being further revolved in either direction to disengage its pintles 22 from extensions of slots 20 and enable said socket 19 to be released and consequently the 5 parts are firmly locked together, the outer shield 21 preventing manipulation of the spring 14 in endeavors to free the parts.

When it is desired to remove a spent or broken lamp the shoulder 23 or band of the 10 lamp as the case may be is pressed together to allow withdrawal of the shield 21 when the spring 14 may be pulled or released from the locking band 12 thus removing the ends 15 from the slots 20 and the plug 17 may 15 then be removed from the socket 19 as ordinarily.

When a lamp or other plug end has a shoulder which will not support a shield of sufficient diameter a contracted thimble resting 20 on the band of the lamp as shown in Fig. 8 may be used and when the locking nut 24 on the socket or other projecting part upon said socket is not large enough for a shield of the required diameter to butt 25 against a washer 25 preferably coned and placed concavely or convexly toward the shield may be secured on the socket say between its locking nut and its body before the shield 21 is positioned thereover as 30 shown in Fig. 9.

If necessary to support the shield when the socket is pendant or the lamp has been broken or removed a spring holder is placed around the socket or the plug with its projecting ends adapted to thrust against the 35 interior face of the shield.

In a modified construction of this invention in place of a complete band carrying the locking spring ends or pins are pieces 40 circumferentially slidably attached to the sockets are substituted and each carries a spring end and has a slot corresponding to the slot in socket and are operated and have the same effect as the band.

45 What I claim as my invention, and desire to secure by Letters Patent is:—

1. In a device for locking electrical plug and socket unions a collar or locking band having slots therein revolvably fitting the 50 socket and carrying a spring with end or ends or pin or pins adapted to engage in the wall of said socket as and for the purposes set forth substantially as herein described and explained.

55 2. In a device for locking electrical plug and socket unions a semi-circular shaped spring adapted to fit upon a locking band and having inturned ends adapted to pass through orifices in the wall of said locking

band as and for the purposes set forth substantially as herein described and explained.

3. An improved locking electrical plug and socket union comprising a socket with slots therein, a locking band over said socket and having slots therein in juxtaposition 65 with the slots in said socket and carrying a spring with intruding end or ends to engage the slots in said socket and an outer thimble or shield to fit over the socket and plug and be retained in position thereon between said 70 socket and a shoulder on said plug by the consummation of the union as and for the purposes set forth substantially as herein described and explained.

4. In an electrical plug and socket connection, means for positively locking the parts together comprising a band provided with holes, spring-pressed pins extending through said holes and engaging orifices in the wall of the socket.

5. In an electrical plug and socket connection, means for positively locking the plug in the socket comprising a band provided with a hole, a spring-pressed pin extending through said hole and engaging an 85 orifice in the wall of the socket.

6. In an electrical plug and socket connection, means for positively locking the plug in the socket, comprising a band having holes therein, spring-pressed pins extending 90 through said holes and engaging slots in the socket and pins on said plug engaging slots in said socket and band.

7. In an electrical plug and socket connection, means for locking the plug in the 95 socket comprising a slotted socket, a band provided with holes, a semi-circular spring embracing said band, said spring having in-turned ends fitting in said holes and engaging the slots in said socket.

8. In an electrical plug and socket connection, means for locking the parts together consisting of a socket having slots therein, a locking band having slots registering with the slots in said socket, spring-pressed pins 105 on said locking band engaging the slots in said socket, a plug having pins engaging the slots in said socket and band, and a housing for said locking band engaging said plug and socket.

In testimony whereof I have signed my name to this specification in the presence of two subscribing witnesses.

WILLIAM STEWART.
